Primary Examiner—M. N. Pandozzi**Attorney, Agent, or Firm—Hawes, Fischer & Dickinson****[57]****CLAIM**

The ornamental design for a combined compartmentalized food tray with windowed sleeve, as shown and described.

DESCRIPTION

FIG. 1 is a top plan view of a combined compartmentalized food tray with windowed sleeve with the tray portion shown separately for convenience of illustration;

FIG. 2 is a front elevational view of the tray portion, this view, the rear elevational view and the side elevational views being of identical design;

FIG. 3 is a bottom plan view of the tray portion;

FIG. 4 is a top plan view of the sleeve portion shown separately for convenience of illustration;

FIG. 5 is a front elevational view of the sleeve portion, this view, the rear elevational view and the left side elevational view being of identical design;

FIG. 6 is a right side elevational view of the sleeve portion;

FIG. 7 is a bottom plan view of the sleeve portion; and,

FIG. 8 is a top plan view of the combined compartmentalized food tray with windowed sleeve showing my new design.
